(57) **CLAIM**

The ornamental design of a water filter cartridge, as shown and described.

DESCRIPTION

FIG. 1 is a top, front, right side perspective view of a water filter cartridge showing my new design;

FIG. 2 is a depiction of the left portion of FIG. 1;

FIG. 3 is a depiction of the right portion of FIG. 1;

FIG. 4 is a front elevation view thereof;

FIG. 5 is a back elevation view thereof;

FIG. 6 is a right side elevation view thereof;

FIG. 7 is a left side elevation view thereof;

FIG. 8 is a top, back, left side perspective view thereof;

FIG. 9 is a depiction of the right portion of FIG. 8;

FIG. 10 is a top, back, right side perspective view thereof;

FIG. 11 is a depiction of the left portion of FIG. 10;

FIG. 12 is a depiction of the right portion of FIG. 10;

FIG. 13 is a top, front, left side perspective view thereof;

FIG. 14 is a depiction of the left portion of FIG. 13;

FIG. 15 is a bottom, back, left side perspective view thereof;

FIG. 16 is a depiction of the right portion of FIG. 15;

FIG. 17 is a bottom, back, right side perspective view thereof;

FIG. 18 is a depiction of the left portion of FIG. 17;

FIG. 19 is a depiction of the right portion of FIG. 17;

FIG. 20 is a bottom, front, left side perspective view thereof;

FIG. 21 is a depiction of the left portion of FIG. 20;

FIG. 22 is a bottom, front, right side perspective view thereof;

FIG. 23 is a depiction of the left portion of FIG. 22;

FIG. 24 is a depiction of the right portion of FIG. 22;

FIG. 25 is a bottom perspective view of the left side thereof;

and,

FIG. 26 is a top perspective view of the left side thereof.

The broken line showing of various features of the water filter cartridge form no part of the claimed design.
